UNITED STATES PATENT OFFICE

WALTER SCHAECHLIN, OF WILKINSBURG, PENNSYLVANIA, ASSIGNOR TO WESTINGHOUSE ELECTRIC & MANUFACTURING COMPANY, A CORPORATION OF PENNSYLVANIA

CAM-ACTUATED DOUBLE-THROW SWITCH

Application filed August 23, 1930. Serial No. 477,337.

My invention relates to control apparatus and more particularly to cam-actuated switches or the like.

An object of my invention is to provide a switch of the cam-actuated type in which there are no sliding contact members.

Another object of my invention is to provide a switch having a movable contact member actuated through a resilient member.

Another object of my invention is to provide means for locking the movable contact of a switch in either of its "closed" or its "open" positions.

A more specific object of my invention is to provide a switch for transferring an electrical connection from one circuit to another which is comparatively simple in construction, effective in operation, and economical of manufacture.

Other objects of my invention will become evident from the following detailed description, taken in conjunction with the accompanying drawings, in which

Figure 1 is a view, in front elevation, of a cam-actuated double-throw switch in its "open" position,

Fig. 2 is a view, in front elevation, of a cam-actuated double-throw switch in one of its "closed" positions, and

Fig. 3 is an exploded view, in perspective, of the double-throw switch showing the details of construction.

The apparatus shown in Fig. 1 comprises fixed contacts 1, a cooperating movable contact 2, connected by a flexible shunt 3 to a support member 4 and held therein by rivets 5. The movable contact 2 is pivotally supported by a pin 6 in contact supports 7 which are pivotally supported by a pin 8 in support member 4. Ears 9 and bosses 10 are provided on the contact-support arms for receiving springs 11.

A work arm 12 is pivotally mounted on support member 4 by pin 8 and has lugs 13 and bosses 14 thereon for engaging springs 11. Rollers 15 are provided in bifurcated projections on the work arm 12 and are supported by pins 16.

A cam 17 is pivotally supported on the cam-support member 18 for cooperating with

the rollers 15 on the work arm. Projections 19 and recesses 20 are provided on the cam to obtain the desired motion of the rollers. A handle 21 for actuating the cam is also provided as an integral part thereof.

The stationary contacts 1 and the support member 4 are located on the bars 22 and are insulated therefrom by rectangular insulating tubes 23. To connect the stationary contacts 1 and the support member 4 to their respective circuits, bus bars 24 are provided.

The operation of the above described apparatus may be set forth as follows:

The cam 17 is turned in a clockwise direction by handle 21. The work arm 12 is caused to rotate also in a clockwise direction by the projection 19 on the cam 17. The movement of the work arm compresses the springs 11 on the righthand side of the lugs 13 on the work arm. Compression of the springs 11 rotates the contact support arms 7 in a clockwise direction, thereby causing movable contact 2 to engage the right-hand fixed contact 1. Further motion of the movable contact-support arms is prevented. The work arm 12 further compresses the springs 11 until the lower roller 15 is positioned in the lower recess 20, thus obtaining the desired contact pressure. It is readily seen that the movable contact 2 is locked in this "closed" position because of the position of the roller 15 on the cam 17, and cannot be opened unless the cam 17 is turned.

The switch is opened by reversing the above procedure. The cam 17 is turned in a counter-clockwise direction by the handle 21.

Provision for locking the movable member of the switch in the open position is made by so shaping the cam that the operation of the movable member is irreversible.

Contact with the left-hand stationary contact is made by moving the cam 17 in a counter-clockwise direction until the upper roller 15 is positioned in the upper recess 20 in the cam 17.

The switch from this position is opened by turning the cam 17 in a clockwise direction.

Although I have shown and described a certain specific embodiment of my invention,

I am fully aware that many modifications thereof are possible. My invention, therefore, is not to be restricted except insofar as is necessitated by the prior art and by the spirit of the appended claims.

5 I claim as my invention:

1. A switch comprising a plurality of stationary contact members, a cooperative movable contact member, said movable contact member being supported by pivotally mounted contact-support arms, a work arm resiliently connected thereto and means for shifting the movable contact member to a plurality of operating positions.

10 2. A switch comprising a plurality of stationary contact members, a cooperative movable contact member, said movable contact member being pivotally supported by pivotally mounted contact-support arms, a work arm resiliently connected thereto and means for shifting the movable contact member to a plurality of operating positions.

15 3. A switch comprising a plurality of stationary contact members, a cooperative movable contact member, said movable contact member being supported by pivotally mounted contact-support arms, a work arm resiliently connected thereto, means for shifting the movable contact member to a plurality of operating positions, and means for locking said movable contact member in any operating position.

20 4. A switch comprising a plurality of stationary contact members, a cooperative movable contact member, said movable contact member being pivotally supported by pivotally mounted contact-support arms, a work arm resiliently connected thereto, means for shifting the movable contact member to a plurality of operating positions and means for locking said movable contact member in any operating position.

25 5. A switch comprising a plurality of stationary contacts, a cooperative movable contact pivotally supported on contact-support arms, said contact-support arms being pivotally supported on a support member, said movable contact and support member being connected by a shunt, a work arm resiliently connected to said contact arms, means for shifting the movable contact to any operating position, and means for locking the movable contact in any operating position.

30 6. A switch comprising two independent stationary contact members, a cooperative movable contact pivotally supported on contact-support arms, said support arms being pivotally mounted on a support member, said support member and movable contact being connected by a shunt, a work arm resiliently connected to said contact-support arms, said work arm having rollers supported by pins in bifurcated projections thereon, a cam co-operating with said rollers to actuate the work arm, thereby moving the contact-sup-

port arms and movable contact to any operating position and so shaped as to lock said work arm and associated members in any operating position.

7. A switch comprising two fixed contacts, a cooperative movable contact, a support member, a shunt connecting the movable contact and support member, two contact-support arms pivotally supporting said movable contact and pivotally mounted on said support member, said support arms having projecting ears and bosses thereon for the mounting of springs, means provided, through a cam action, to actuate said springs, thereby moving the contact-support arms and contact to any operating position and means for locking them in any operating position.

75 8. A switch comprising two stationary contacts, a cooperative movable contact connected by a flexible shunt to a support member of high conductivity, two contact-support arms pivotally supporting said movable contact and pivotally supported on said support member by a pin, said contact-support arms having projecting ears and bosses thereon to receive springs for actuating them, a work arm having projecting lugs and bosses to actuate said springs and pivotally mounted on the said support member by the aforesaid pin, said work arm being also shaped to receive two rollers in bifurcated projections thereon, means for moving said work arm and thereby actuating the said moving contact to any operating position and means for locking said work arm, thereby locking the movable contact in any operating position.

85 9. A switch comprising two stationary contacts, a cooperative movable contact connected by a flexible shunt to a support member of high conductivity, two contact-support arms pivotally supporting said movable contact and pivotally supported on said support member by a pin, said contact-support arms having projecting ears and bosses to receive springs for actuating them, a work arm having projecting lugs and bosses to actuate said springs and being pivotally mounted on the said support member by the said pin, said work arm also shaped to receive two rollers in bifurcated projections thereon, a cam co-operating with said rollers and pivotally mounted on a cam-support member, said cam being of such shape as to cause motion of said work arm to compress said springs, thereby moving the said contact-support arms and movable contact carried thereby to either of the two "closed" positions or to "open" position and also of such shape as to lock said movable contact in either of the "closed" positions or in the open position, said cam being also formed to provide a handle for actuating the switch.

90 10. In a switch comprising, in combination, a receiving contact member, a movable contact member disposed to engage the receiving

contact member, a work arm for actuating the movable contact member into and out of engagement with the receiving contact member, a resilient member interposed between the work arm and the movable contact member, and a cam for positively actuating the contact member to its different positions.

- 5 11. In a switch comprising, in combination, a receiving contact member, a movable contact member disposed to engage the receiving contact member, a contact support arm for supporting the movable contact member, a work arm for actuating the movable contact member into and out of engagement with the receiving contact member, a support member for pivotally supporting the work arm, rollers mounted on the work arm, a cam disposed to cooperate with the rollers for positively actuating the movable contact member to its different positions, a resilient member interposed between the work arm and the movable contact member to provide suitable contact pressure, and a shunt for connecting the movable contact member to the support member.
- 10 12. In a switch comprising, in combination, a receiving contact member, a movable contact member disposed to engage the receiving contact member, contact support arms for supporting the movable contact member, a work arm for actuating the movable contact member into and out of engagement with the receiving contact member, a support member for pivotally supporting the work arm, a plurality of rollers mounted on the work arm, a cam disposed to cooperate with the rollers for positively actuating the movable contact member to its different positions and of such shape as to lock the movable contact member in any operating position, a resilient member interposed between the work arm and the movable contact member to provide suitable contact pressure, and a flexible shunt for connecting the movable contact member to the support member.
- 15 45 In testimony whereof, I have hereunto subscribed my name this 21st day of August, 1930.

WALTER SCHAEELCHLIN.
